TREATMENT OF HYDROCARBON OILS

Joseph G. Alther, Chicago, Ill., assignor, by mesne assignments, to Universal Oil Products Company, Chicago, Ill., a corporation of Delaware

Application February 16, 1931, Serial No. 516,020
Renewed May 20, 1935

1 Claim. (Cl. 196—60)

This invention relates to the treatment of hydrocarbon oils, and refers more particularly to the simultaneous treatment and conversion of the unvaporized residual liquid product and the gases resulting from the pyrolysis or cracking of hydrocarbon oils.

In the treatment of hydrocarbon oils primarily to convert the same into lower boiling products less valuable by-products are obtained, such as a relatively heavy unvaporized oil and/or a carbonaceous residue and gases, all of which are generally used for fuel purposes. It is among the objects of the present invention to further convert the unvaporized liquid residue and the gases, into more valuable low boiling products.

In one of its specific embodiments the invention provides a process which comprises subjecting heavy hydrocarbon oils to treatment at elevated temperatures and pressures while simultaneously subjecting the gaseous products of the cracking process mixed with similar extraneous gases to a similar treatment at elevated temperatures and pressures, combining the liquid and gaseous streams so as to produce an intimate mixture thereof, introducing the mixture of hydrocarbon liquids, vapors and gases into a large reaction zone wherein separation of vapors and liquids is effected, passing the vapors from the reaction zone preferably through a reheating and reconversion zone prior to admission to primary fractionating devices for the production of vapors of desired boiling point range which are cooled, condensed and collected, preferably passing heavy liquids from the auxiliary vaporizing chamber to the treating zone for further conversion and returning reflux condensates along with preheated raw oil from the auxiliary fractionator to the primary fractionator.

To enable an accurate description of a particular operation of many falling within the scope of the invention the attached drawings are provided which show diagrammatically in Fig. 1 an arrangement of apparatus and equipment which may be employed.

Heavy hydrocarbon oil charging stocks typified by the residue produced in the topping of crudes or heavy hydrocarbon oil mixtures from any source may be taken by pump 3 from line 1, containing valve 2, and discharged through line 4, containing valve 5, to auxiliary fractionator 6 wherein heat exchange is effected and the preheated raw oil mixed with reflux condensates passed out through line 7 containing valve 8 to pump 9. The vapors from the auxiliary fractionator pass through line 66, containing valve

67, to auxiliary condenser 68 in which cooling is effected with condensation of liquid products, the cooled products passing to line 69, containing valve 10, to receiver 11 which is provided with line 12, containing valve 13, for the release of fixed gases and line 14, containing valve 15, for the withdrawal of liquid of approximately desired boiling point range.

Pump 9 discharges through line 10, containing valve 11, into primary fractionator 12, in which the vapors from the conversion zone are undergoing fractionation, the incoming oil being further preheated and partially fractionated and combined with reflux condensates leaving through line 13, containing valve 14, to pump 15. Pump 15 discharges through line 16 and valve 17 into heating element 18 disposed in furnace 19. During passage through the heating element temperature and pressure conditions are attained sufficient to insure desired conversions and the heated materials leave through line 20, containing valve 21, to enter mixing device 23 which may be of types more fully described with reference to Figs. 2 and 3. Preheated gas mixtures are introduced to the mixer from line 65, as will be later more fully described. In mixer 23 an extremely intimate commingling of products is effected, the mixture passing through line 24, containing valve 25, to enlarged chamber 26 which is provided to allow time for the completion of conversion reactions.

Chamber 26 is preferably thoroughly insulated to conserve heat. Temperatures employed at the outlet of the heating element are those characteristic of the temperatures employed in commercial cracking operations and may be of the order of 750 to 1000° F., more or less, and pressures employed during the reaction period ensuing in chamber 26 may be high superatmospheric up to 500 pounds per square inch or higher. The vapors from the reaction chamber pass through line 27 containing valve 28 either directly through valve 28' to primary fractionator 12, which typifies any suitable arrangement of equipment for separating low boiling liquids of desired characteristics or preferably through line 76, containing valve 77, to supplementary heating element 78 disposed in furnace 79, the reheated vapors passing through line 80, containing valve 81, back to line 28 and thence to fractionator 12 as before, this fractionator receiving from line 53 a certain portion of the end product liquids to control boiling point range, as will be later more fully described, and from line 10 a mixture of preheated raw oil and certain intermediate fractions from

the bottoms produced in reaction chamber 26. The pressures employed in fractionator 12 are preferably of the same order as those employed in the conversion zone.

Heavy liquid accumulations in reaction chamber 26 pass through line 29 and valve 30, preferably with pressure reduction to approximately atmospheric or relatively low superatmospheric pressure to auxiliary vaporizing chamber 31 in which evolution of light fractions is permitted, these passing through line 32, containing valve 33, to auxiliary fractionator 6. Chamber 31 is also provided with line 34, containing valve 35, as an outlet for liquid residues, line 34 branching 15 into line 38, containing valve 39, which permits withdrawal of heavy liquids from the process and line 34', containing valve 35', leading to pump 36' which discharges into line 36, containing valve 37, leading to line 16, thus enabling the retreatment and reconversion of all or a portion of the heavy liquids from the chamber in the treating zone.

Vapors from fractionator 12 pass through line 40, containing valve 41, and through condenser 42 which effects partial condensation and cooling, the cooled products passing through line 43, containing valve 44, to receiver 45. Line 50, containing valve 51, leading to pump 52 permits the utilization of suitable portions of the end product 20 liquids for the control of boiling point range of vapors, these liquid portions being discharged through line 53, containing valve 54, to fractionator 12 as already indicated.

Receiver 45 is also provided with line 48, containing valve 49, for the withdrawal of low boiling liquid products of the process and line 46, containing valve 47, to permit the release of excess accumulations of fixed gases. Branch line 55, containing valve 56, leads from line 46 to 40 pump 57, which also receives outside hydrocarbon gases from line 58, containing valve 59.

As examples of gas mixtures extraneous to the process which may be employed may be mentioned cracked gases from other units similar 45 to the one described, or other types of cracking units, natural gas, petroleum refinery gases, coal gas, oil gas, water gas, etcetera. Pump 57 discharges gas mixtures through line 60, containing valve 61, into and through heating element 62 disposed in furnace 63, the gases being heated to suitable temperatures for their subsequent reactions in mixer 23 and the reaction chamber following, being introduced into mixer 23 through line 65 and valve 64, as already indicated. Temperatures to which the gas mixtures may be pre-heated may vary with the composition of the mixtures employed, the nature of the raw oil charging stock and the conditions obtaining in the conversion zone, but will generally be of the order of from 800 to 1200° F., more or less. The reactions induced supplementary to the ordinary cracking reactions by the introduction of the heated gas mixtures are substantially those of saturating with hydrogen constituents which 65 would normally appear as unsaturated or olefinic compounds and the polymerizing of certain light unsaturated hydrocarbon radicals to low boiling liquids. The reactions, therefore, result in minimizing the production of pitch or coke 70 under any given set of conditions and of materially increasing the yields of light hydrocarbons obtainable as will be shown by examples given later in the specification.

Fig. 2 of the attached drawings illustrates diagrammatically one form of mixing device which

may be utilized in an apparatus such as that above described for intimately commingling the vapors and the oil from the two heating elements. Oil from the heating element 18 is introduced to the mixing device through line 20 and is discharged from cup or deflector A into the uppermost of a series of rapidly revolving discs B, C and D. Discs B, C and D are mounted on shaft E, supported at one end by an alignment and thrust bearing F, which may, if desired, be cooled in any suitable manner (not shown); for example, by circulating cold oil therethrough. Shaft E is packed at G, where it passes through the outer shell H of the mixing device, and the stuffing box I may be cooled by radiating fins J, or in any other suitable manner. Shaft E and the attached discs are rapidly rotated by any suitable means (not shown), such as, for example, an electric motor, a steam driven turbine, or any other motivating means. Gases from heating element 62 introduced to the mixing device through line 65, pass upward around the rapidly revolving discs D, C and B, coming in contact with the liquid introduced through line 20, which is substantially atomized and vaporized by impingement upon the rapidly revolving discs and hurled by the centrifugal force of the revolving discs into the stream of gases passing through the apparatus. The vapors, gases and atomized liquid thus intimately commingled in the apparatus pass through line 24 to reaction chamber 26.

Fig. 3 of the attached drawings illustrates another suitable form of mixing device which may be employed for injecting the oil from heating element 18 into the stream of gases from heating element 62. The heated gases are introduced through line 65 and their velocity is greatly increased by means of nozzle K as they pass into line 24. Heated oil from heating element 18, introduced through line 20 to the zone L, surrounding nozzle K, is impelled by the high velocity of the gases passing from nozzle K through chamber M to line 24 through the orifice N into the stream of gases and is intimately commingled with said stream of gases passing therewith through line 24 to reaction chamber 26.

The descriptions given with reference to the three figures are illustrative of methods and means which may be employed within the scope of the invention, but are not to be construed in a limiting sense as many other types of apparatus may be employed without departing therefrom.

As examples of the results obtainable by the operation of my invention, a Mid-Continent 24-26° A. P. I. gravity fuel oil is considered as 55 charging stock. When the gas is not returned to the process, approximately 50% of gasoline of high anti-knock quality may be produced from this charging stock with a yield of approximately 35% of fuel residue, which is fluid when heated, 60 and approximately 400 cubic feet of gas per barrel of charge. By returning the gas to the system and treating in the manner described, one may obtain under the same conditions of treatment approximately 55% of gasoline, the same quality of fuel oil residue, and the gas produced is reduced to approximately 250 cubic feet per barrel of raw oil.

Conditions of treatment in the operation herein considered are a transfer temperature of the oil 70 leaving the heating element of approximately 900° F., a pressure on the heating element and reaction chamber of approximately 250 pounds per square inch, approximately 30 pounds per square inch pressure on the vaporizing chamber 75

and equalized pressure therewith on the fractionator, condenser and receiver. The temperature to which the gas is heated is approximately 1000° F. to which approximate temperature the vapors emergent from reheating element 78 are also heated.

In the treatment of a 40-42° A. P. I. gravity Pennsylvania crude oil distillate, one may obtain a yield of 65% of gasoline having an anti-knock 10 value of approximately 55% benzol equivalent, that is, equal to a mixture of Pennsylvania straight run gasoline and benzol containing 50% of the latter, approximately 20% of fuel oil residue and approximately 400 cubic feet of gas per 15 barrel of raw oil.

I claim as my invention:

A process for cracking hydrocarbon oil and for conjointly converting the residue and the incondensible gases of the cracking process into low 20 boiling oils, which comprises maintaining hydrocarbon oil under cracking conditions of temperature and superatmospheric pressure in a reaction zone, separately removing from the reaction zone unvaporized oil and a mixture of vapors and in-

condensible gases, heating said mixture to vapor phase cracking temperature and then dephlegmating the mixture to condense insufficiently cracked fractions thereof as reflux condensate, flash distilling the withdrawn unvaporized oil by pressure reduction thereby forming residue, combining such residue and the reflux condensate with charging oil for the cracking process and passing the commingled oils in a restricted stream through a heating zone, heating the commingled 10 oils to cracking temperature under superatmospheric pressure in the heating zone and then discharging the same into said reaction zone, further cooling the dephlegmated mixture of vapors and gases to condense the vapors out of the gases 15 and separating the resultant condensate from the gases, heating a substantial portion of the separated gases to reaction temperature and commingling the same with the heated oils discharged from the heating zone into the reaction 20 zone to react with the heated residue in the reaction zone.

JOSEPH G. ALTHER.
